UNITED STATES PATENT OFFICE.

WILLIAM ROBINSON, OF CHURDAN, IOWA.

SHEARS FOR CUTTING METAL BOLTS.

SPECIFICATION forming part of Letters Patent No. 403,961, dated May 28, 1889.

Application filed January 26, 1889. Serial No. 297,716. (No model.)

To all whom it may concern:

Be it known that I, WILLIAM ROBINSON, a citizen of the United States, residing at Churdan, in the county of Greene and State of Iowa, have invented new and useful Improvements in Shears for Cutting Metal Bolts, &c., of which the following is a specification.

The invention relates to improvements in shears for cutting metal bolts, &c.; and it consists in a certain novel construction and combination of devices, fully described hereinafter in connection with the accompanying drawings, and specifically pointed out in the appended claim.

15 In the drawings, Figure 1 is a perspective view of shears embodying my improvements. Fig. 2 is a side view of the same, showing the jaws open. Fig. 3 is a detail perspective view of the base.

20 Referring by letter to the drawings, A designates the base, which is arranged on a table or stand, B, of any suitable form and construction to sustain the operating parts of the shears. This base is provided with a central elevated portion, a, and depressed portions a' a' on opposite sides thereof, the said depressed portions being perforated to receive the securing-bolts b b. This base is also provided at one end with the upwardly-projecting parallel ears C C, between which the operating-lever D is pivoted, the pivot-bolt d being arranged in perforations in the said ears.

25 E represents a blade-carrying lever, which is pivoted near its center to the elevated portion of the base by the pivot-bolt e, and it extends rearwardly and upwardly until its extremity is above the inner end of the operating-lever, to which it is connected by the links F F. These links are arranged, respectively, on opposite sides of the said levers and are pivoted thereto by suitable transverse bolts, f and f'.

30 The blade-carrying lever is provided at its front end with a cutting-knife, G, which is mortised in the lever and secured thereto by means of bolts in the ordinary manner, and a similar cutting-knife, G', is mortised in the

forward end of the base to act in conjunction with the knife G.

35 The links which connect the rear upwardly-bent end of the blade-carrying lever to the operating-lever are connected to the latter close to its pivot, so as to afford as great leverage as possible, and when the shears are 50 in the act of cutting the links are in an approximately vertical position and press the rear end of the blade-carrying lever upward; hence the advantage in bending the rear end of the said blade-carrying lever upward. 55

40 The outer end of the elevated portion a of the base beyond the pivot of the blade-carrying lever, to which the knife G' is secured, is inclined along its upper edge, whereby a similar inclination may be given to the cutting-knife, and the said pivot is arranged slightly below the upper edge of the knife G', whereby a shear action is imparted to the knives in cutting.

45 Having thus described the invention, I claim—

50 In metal-shears, the combination, with the base A, provided with the intermediate elevated portion, a, carrying a stationary knife, G', and the depressed perforated portions a' a', near the extremities of the base, of the blade-carrying lever E, fulcrumed to the elevated portion of the base below the level of the upper edge of the stationary knife and curved upwardly toward its rear end over the 55 depressed rear end of the base, the operating-lever D, fulcrumed to the base beneath the upwardly-curved end of the blade-carrying lever, and the links connecting the extremities of the upwardly-curved portion of the 60 blade-carrying lever to the shorter arm of the operating-lever, whereby an upward thrust is imparted to the end of the blade-carrying lever, substantially as specified.

55 In testimony that I claim the foregoing as 65 my own I have hereto affixed my signature in presence of two witnesses.

WILLIAM ROBINSON.
